ACCIDENT CHART

Arnold Brown, Worcester, Mass.

Application March 12, 1952, Serial No. 18,860

Term of patent 14 years

(Cl. D25—1)

To all whom it may concern:

Be it known that I, Arnold Brown, a citizen of the United States, residing at Worcester, county of Worcester, and State of Massachusetts, have invented a new, original and ornamental design for an Accident Chart, of which the following is a specification, reference being had to the accompanying drawing, forming part thereof.

Fig. 1 is a plan view of one side of an accident chart, showing my new design; and

Fig. 2 is a plan view of the other side thereof. The chart is of no appreciable thickness.

I claim:

The ornamental design for an accident chart, as shown and described.

ARNOLD BROWN.
